(57) **CLAIM**

The ornamental design for a cat scratch pad for claws, as shown and described.

DESCRIPTION

FIG. 1 is a front perspective view of a cat scratch pad for claws, showing my new design.

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is another front perspective view, but shown with the belt in a rolled-up configuration;

FIG. 10 is another front perspective view thereof, but shown in a usage state in an environmental view;

FIG. 11 is an enlarged detail view of area 11 in FIG. 1; and, FIG. 12 is an enlarged detail view of area 12 in FIG. 2.

The broken lines shown in FIG. 10 illustrate an environmental structure that forms no part of the claimed design.

FIGS. 1, 2, 11 and 12 show broken lines that represent the boundaries and indicators of the enlarged views. The broken lines form no part of the claimed design.
